(57) **CLAIM**

The ornamental design for a door facing, as shown and described.

DESCRIPTION

FIG. 1 is a front perspective view of my design, with the rear perspective view being a mirror image thereof;
FIG. 2 is a front elevational view of FIG. 1;
FIG. 3 is a magnified view of a portion of FIG. 2;
FIG. 4 is a front perspective view of a first variation of my design, with the rear perspective view being a mirror image thereof;
FIG. 5 is a front elevational view of FIG. 4; and,
FIG. 6 is a magnified view of a portion of FIG. 5.

The evenly spaced broken lines depict portions of the door facing that form no part of the claimed design. The dot-to-dash broken lines in FIGS. 2 and 3 and FIGS. 5 and 6 depict the limits of the enlarged view and form no part of the claimed design.
